UNITED STATES PATENT OFFICE.

AUGUSTE LEVESQUE, OF NEW BEDFORD, MASSACHUSETTS.

TROLLEY-POLE.

1,065,818.

Specification of Letters Patent. Patented June 24, 1913.

Application filed October 9, 1911. Serial No. 653,632.

To all whom it may concern:

Be it known that I, AUGUSTE LEVESQUE, a citizen of the United States, residing at New Bedford, in the county of Bristol and State 5 of Massachusetts, have invented certain new and useful Improvements in Trolley-Poles; and I do hereby declare the following to be a full, clear, and exact description of the invention, such as will enable others skilled 10 in the art to which it appertains to make and use the same.

This invention relates to trolley pole attachments and has for its object to provide a device of this nature wherein constant 15 pressure will be exerted in a vertical plane directly upon the wire.

Heretofore in the construction of trolley poles a pressure has been exerted upon the wire from springs located at the base of the 20 pole, there being no independent pressure adjacent to the wheel or roll. The distance between the trolley wheel or roll and the base of the pole where the pressure is exerted greatly decreases the force of the pressure 25 and increases the liability of the wheel or roll to jump the wire.

It is the object of the present invention to overcome this objectionable feature by providing independent pressure for the wheel 30 or roll at the upper terminal of the trolley pole, which pressure in combination with the pressure now in use, will greatly increase the practical merit of trolley poles and insure the non-jumping of the wheel.

With the above and other objects in view, this invention consists in the construction, combination and arrangement of parts, all 35 as hereinafter more particularly described, claimed and illustrated in the accompanying drawings, wherein:

Figure 1 is an elevation of the outer terminal of a trolley pole, embodying the present invention, illustrating the same coöperating with the wire; Fig. 2 is a plan top 40 view thereof; and Fig. 3 is a vertical section taken along line 3—3 of Fig. 1.

Referring more particularly to the drawings 10 indicates a trolley pole attached to a car in any suitable manner, having its 45 upper terminal flattened as at 11 to rest in

a horizontal plane, said flattened portion 11 being provided with a central, internally threaded opening 12. A cup or cylinder 13 is threaded into the opening 12 at its upper terminal, and is provided with an orificed 55 closure 14 which is threaded into the interior of the cup. A piston rod 15 reciprocates through the opening of the closure 14 and carries a detachable piston 16 at its lower terminal. A spring 17 is interposed between 60 the piston 16 and the bottom of the cup or cylinder 13 and normally tends to force the piston rod upwardly. At the upper terminal of the piston rod is formed a yoke 18 between the arms of which is rotatably mounted 65 a trolley wheel 19 through the instrumentality of the shaft 20. Thus it will be seen that the action of the spring 17 forces the trolley wheel 19 into engagement with the trolley wire 21, thereby insuring the 70 positive engagement therewith and the additional pressure exerted by said spring also eliminates the liability of said wheel jumping the wire 21.

A brace 22 is interposed between the base 75 of the cylinder 13 and the oblique portion of the main body portion of the trolley pole 10, and is adapted to normally rest at right angles to said trolley pole. A bolt 23 pierces the trolley pole and secures the adjacent 80 terminals of the brace 22 thereof through the instrumentality of the nut 24. A spring 25 is secured to the bolt 23 and carries at its free terminal a yoke 26, said yoke being pivotally connected to the projecting 85 terminals of the shaft 20.

From this construction it will be obvious that the trolley wheel 19 is retained in positive engagement with the wire 21, and that the mechanism at the top of the pole is 90 thoroughly braced and will in no way become loose by the jars to which the pole is subjected.

Having thus fully described my invention, what I claim as new and desire to secure by U. S. Letters Patent, is—

In a trolley, the combination with a trolley pole, a cylinder, means for connecting said cylinder to the trolley pole, a piston reciprocating in the cylinder, a spring in- 100

terposed between the piston and the cylinder, a harp supported by said piston, a trolley wheel mounted in the harp, a U-shaped yoke pivotally connected to the harp, a bolt 5 passing through the trolley pole and having an eye formed on one end thereof, and a coil spring connecting said yoke to the bolt.

In testimony whereof I affix my signature in presence of two witnesses.

AUGUSTE LEVESQUE.
